COMBINED TOWEL DISPENSER AND TRASH RECEPTACLE

William F. Martin, 350 Stonycroft Road,
Ridgewood, N.J. 07450

Filed Sept. 20, 1974, Ser. No. 507,736

Term of patent 14 years

Int. Cl. D7—07

U.S. Cl. D7—191

FIG. 1

FIG. 2

FIG. 3

FIG. 5

FIG. 4

FIG. 6

FIG. 1 is an isometric view of a combined towel dispenser and trash receptacle showing my new design;

FIG. 2 is a front elevational view thereof;

FIG. 3 is a right side elevational view thereof;

FIG. 4 is a top plan view thereof;

FIG. 5 is a rear elevational view thereof; and

FIG. 6 is a bottom plan view thereof.

I claim:

The ornamental design for a combined towel dispenser and trash receptacle, as shown.
